(57) **CLAIM**

The ornamental design for a hood to cover a hinge, as shown and described.

DESCRIPTION

FIG. 1 is a front elevation view of a hood to cover a hinge showing our new design;

FIG. 2 is a rear elevation view thereof;

FIG. 3 is a top perspective view thereof;

FIG. 4 is a top plan view thereof; and,

FIG. 5 is a right elevation view thereof; the left elevation view being a mirror image thereof.

The broken lines shown in the figures are included for the purpose of illustrating portions of the article and form no part of the claimed design.
